UNITED STATES PATENT OFFICE.

WILLIAM FRITZ, OF PHILADELPHIA, PENNSYLVANIA.

CANDY-COATING MACHINE.

1,223,687.

Specification of Letters Patent. Patented Apr. 24, 1917.

Application filed April 3, 1915. Serial No. 18,875.

To all whom it may concern:

Be it known that I, WILLIAM FRITZ, a citizen of the United States, residing in the city and county of Philadelphia, State of Pennsylvania, have invented a new and useful Candy-Coating Machine, of which the following is a specification.

My invention consists of a machine for coating candy or similar confectionery, in which blanks are fed between sprays or sheets of chocolate in a solution of a required or desired consistency, and thereupon drying such coated pieces.

It further consists of such a machine in which the blanks are evenly coated and kept separate until dried and ready for packing.

It further consists of such a machine in which the coating upon the blanks is evenly spread by the supports and feeders being reciprocated and shaken while being carried through the machine.

It further consists of other novel features of construction, all as will be hereinafter fully set forth.

The annexed drawings and the following description set forth in detail one mechanical form embodying the invention, such detail construction being but one of various mechanical forms in which the principle of the invention may be used.

In the drawings—

Figure 1 represents a longitudinal section of my machine for coating confectionery blanks with chocolate.

Fig. 2 represents a top plan view of the machine.

Fig. 3 represents a diagrammatic side elevation of the machine.

Fig. 4 represents a transverse section of one of the pumps.

Fig. 5 represents a transverse section of one of the spraying pipes.

Fig. 6 represents a detail view of one end of a roller-shaft.

Fig. 7 represents a detail view of one of the plates operating in moving the coated confectionery.

Figs. 8, 9 and 10 represent detail views of means for forming ornamentation upon the coating.

Fig. 11 represents a detail view of adjusting means for disks.

Similar numerals of reference indicate corresponding parts in the figures.

Referring to the drawings, the reference numeral 1 indicates a tank, mounted on legs,

2, and having an inlet, 3, near its top and an outlet, 4, at its bottom, by means of which such tank is supplied with a fluid, such as steam or hot water, to maintain an even temperature in the tank. A container, 5, is secured from the upper end of the tank, to form a chamber, 6, having a semicylindrical bottom, 7, and two vertical walls, 8. A shaft, 9, is journaled in the side-walls of the tank and container, and is axial to the semicylindrical bottom of the latter, and blades or paddles, 10, are radially secured to such shaft to agitate the liquid coating in the container and maintain it at a predetermined temperature and consistency. A cylindrical piston-chamber, 11, is located beneath the tank and container, and has a roller, 12, journaled in the same, eccentrically to the piston-chamber and having a piston-blade, 14, slidably and diametrically supported in a longitudinal slot, 15, in the roller, with its longitudinal edges in tight but movable fit upon the interior of the wall of the piston-chamber. A pipe, 16, extends from the bottom of the container to the upper side of the piston-chamber, and a pipe, 17, extends upward, parallel to said pipe, from the top of said chamber and out through the open top of the stirring chamber. A valve, 18, is provided in the bottom of the piston-chamber, through which the contents of said chamber may be drawn when the machine is stopped for cleaning or similar purpose.

Two pairs of uprights, 19 and 20, are provided at the feeding-end of the machine, and a transverse roller, 21, is journaled in the upper ends of the uprights 19 and another transverse roller, 22, is journaled in the upper ends of the uprights 20, parallel to the feed-edge of the open tank and an endless apron, 131, is fitted to travel around said rollers to have its upper portion in a horizontal plane above the upper edge of the tank, and transverse strips, 132, secured upon its outer surface at predetermined relative distances. The inner transverse roller 22 is of larger diameter than the outer roller 21, which has horizontally adjustable bearings, 23, for adjusting the tension of the apron. A roller, 24, has its ends journaled in horizontally adjustable bearings, 25, below the outer roller 21, and a roller 26 has adjustable bearings, 27, and is journaled below the large-diameter roller 22. Elastic bands, 29, preferably formed from coiled wire, pass

around the rollers, and bear against the outer face of the horizontal portion of the apron. A table, 30, is provided at the outer roller, in horizontal alinement with the horizontal portion of the apron, and with its edge closely approached to the latter. Said feeding table has preferably longitudinal grooves, 31, which correspond with their ends with the spaces between pairs of the peripheral bands upon the horizontal traveling apron.

A pair of transverse rollers, 32, are journaled above the transverse edges of the stirring chamber with the uppermost portions 15 of their peripheries in a horizontal plane with the feeding apron, and said rollers have an endless apron, 35, of suitable open-work construction, a suitable form of which is seen in Fig. 2, forming a continuance of the 20 bands of the feeding table. A transverse board, 34, is supported between the inner feeding roller and the adjoining roller 32 to connect the feeding table and the apron upon the last described rollers. The upper 25 right pipe 17 has a transverse pipe, 36, at its upper end, formed with a series of spray-openings or ports, 37, or a narrow slot, in its lower side. This latter pipe extends across the machine and has a downwardly bent portion, 38, at the end, from the lower end of which a perforated or slotted pipe, 39, passes beneath the upper portions of the endless apron and has its end closed at the opposite side of the machine frame. The transverse 35 spray-pipes have valve-tubes, 40 and 41, fitted in their interiors and have port-openings, 42 and 43, which tubes by rocking them, can more or less cover or uncover the port-openings in the spray-pipes. The valve-tubes can be adjusted within the spray-pipes to discharge the coating liquid in the desired 40 quantities by turning the valve-tubes and securing them by screws, 44, in peripheral slots, 45, in the spray-pipes. The apron 45 carries the blanks or fillings, 46, to be coated, between the upper and lower spray-pipes, covering the blanks with the liquid coating, and the upper portion of the apron has a transverse bar, 47, bearing against it from below and has secured at its ends two levers, 48, fulcrumed upon the sides of the machine-frame to rock in vertical planes. Cams, 49, are secured upon transverse shafts, 50, in the frame and will engage and rock the levers 55 as the shafts are rotated, and the transverse bar will shake the net-apron to shake surplus coating from the blanks.

Bearings, 51, are supported upon the side-frames at short distances beyond the rollers 60 around which the net apron travels, and transverse shafts, 52, are journaled in said bearings with their axes in about the level of the upper spray-pipe, and each of said shafts has disks, 53, formed with radial and 65 slightly outwardly widening notches, 54, in

their peripheries,—four notches being here illustrated in each disk. Sprocket-wheels, 55, are secured to the shafts and two sprocket-chains, 56, pass around said wheels to be driven in unison. Flat strips, 57, are secured at regular intervals to links of said chains to successively engage with their ends in the inner ends of the notches in the disks, and said strips are spaced to correspond to the length of the blanks or cores of the candy 75 and have outwardly projecting pins, 105, so as to move transverse rows of such blanks toward the discharge end of the machine, one row at a time. The disks have peripheral grooves, 106, and elastic bands, 107, run in 80 such grooves to permit of the requisite resiliency.

Three pinions, 58, 59 and 60, of the same diameters, are supported at the discharge ends of the coil-bands upon each side of the 85 machine frame, the pinions 58 and 60, being secured upon the ends of two shafts, 61 and 62, journaled in the sides of the machine frame and one shaft 62 being revolved by connection with the revolving elements of 90 the machine.

One idle pinion 59 is journaled in each set to mesh with the pinions 58 and 60, being rotatable upon a stud, 63, in a horizontal line with the ends of the shafts, and the ends of 95 the shafts carry cams, 64, which engage the lower edges of vertically movable flat bars, 65, upon the sides of the machine frame and each having a vertical slot, 66, at its middle and engaged by a stud, 67, upon the face of 100 the middle pinion. Transverse rods, 68, are secured at their ends in the sides of the machine frame at the discharge end of the coiled bands carrying the blanks, and longitudinal blades, 69, are longitudinally secured 105 upon said rods to receive the blanks upon their upper edges from such bands. A transverse rod, 70, has a number of blades, 71, secured to it between the rigid blades, and said rod is secured at its ends upon the 110 slotted bars 65, which bars are raised, moved forward, lowered and moved backward with their upper edges above the edges of the stationary blades to raise the blanks from the latter, moving them to the discharge end 115 above the stationary blades, and discharging upon an endless apron, 117, forming a horizontal traveling surface by passing around a large-diameter roller, 118, and a small diameter roller, 119. A flat casing 120, open 120 at both ends, is supported over the horizontal portion of the apron, and has an inclined hood, 121, open through the upper wall of the casing and above the discharge end of the casing, where such opening has a sliding gate, 131. A cooling box, 122, has a coil, 123, having an air-inlet, 124, at one end and an outlet, 125, connected to a blower, 126, forcing air into the hood, through a duct, 127, and creating a cooled current of air 130

meeting the coated confections and drying them. A box, 77, incloses the feeding and coating elements and has openings, 78 and 79, in its ends, adjustably opened and closed by gates, 80 and 81, so that the blanks can pass through the coating chamber and be kept at substantially the same temperature on its travel.

Tubes, 82, are supported upon the upper 10 coating or spray pipe and extend toward the discharge end of the machine, where each tube has a flexible portion, 83, and a nozzle, 84, having a downwardly pointing nipple, 85, registering with the longitudinal rows of 15 coated candy-pieces passing through the machine. A bar, 86, is supported to transversely reciprocate beneath the movable nozzles and has seats 87 for the same, to impart lateral movements to the nozzles movably 20 supported in said reciprocating seats. A lever, 88, is fulcrumed to be laterally rocked and has one limb pivotally connected to the transversely movable bar and a bent stub, 89, at its other limb which bears against an 25 similar series of cam or ratchet teeth, 90, upon the face of a sprocket-wheel, 91, meshing with a sprocket-chain 92.

A transverse tube, 93, formed with eccentric pump-cyl'nders, 94, one for each path 30 of coated blanks,--has a shaft, 95, journaled in it with diametrical slots, 96, in which piston blades, 97, are slideable with their edges bearing against the walls of the pump-cylinder. The pump-shaft has a sprocket-wheel, 98, upon one end, and an arm, 99, is pivoted at its inner end upon the end of the shaft and has a pawl, 100, upon its outer end, engaging said sprocket-wheel. A connecting rod, 101, is pivoted at one end to said rock- 40 arm and pawl and at the other end to the face of the sprocket-wheel 91.

The shafts of the peripherally grooved rollers which carry the apron through the coating chamber have slotted ends, 102, en- 45 gaged by tongues, 103, upon the ends of shaft-sections rotatable and slideable in bearings 104, in the machine frame to connect and disconnect the rollers.

The grooved disks 53 are longitudinally 50 loose upon their shafts to admit of them being adjusted upon the same, and two trans- 55 verse screws, 110 and 111, are journaled parallel with the shafts and have pinions, 112, upon their ends meshing with each other and 60 one shaft has a knob or handle, 113, for revolving it. The grooved disks are straddled by forks, 114, which have each a trans- 65 verse smooth slot, 115, and a threaded bore, 116, in their shanks, which alternately en- 70 gage one and the other of the screws, so that pairs of disks can simultaneously be brought together or spread apart upon the screws and shafts.

In practice, the grooved feeding table has 75 its grooves filled with the blanks or cores to

be coated and are fed over upon the traveling apron in transverse rows and separated by the bands traveling with the apron to the traveling coating apron. The blanks are sprayed from above and below through the 80 ports of the transverse spraying pipes, and the elastic apron is shaken by the transverse bar beneath the blanks, to shake the surplus of the liquid coating from the blanks and to 85 smooth such coating. The pump beneath 75 the stirring chamber forces the liquid coating up through the pipe and sprays the same over the blanks, and the surplus liquid falls back in the stirring chamber. The carriers above the traveling elastic apron have their 90 pins engaging the blanks, and help to shake and feed the coated confections. As the 95 coated articles leave the apron, they slide out on the edges of the blades, the movable ones of which move the coated articles to 100 the cooling casing. The cool draft of air blown into the casing near its discharge, will retard the coated confections and properly cool the same.

The tubes having the vibrating ends and 105 nozzles upon such ends form serpentine or waved ornamented string patterns upon the upper sides of the pieces of candy, the ends of which strings are drawn thin when they are drawn out and severed between the two 110 pieces of candy.

Other modes of applying the principle of my invention may be employed for the mode herein explained. Changes may therefore be made as regards the mechanism thus disclosed, provided the principles of construction set forth, respectively, in the following 115 claims are employed.

Having thus described my invention, what I claim as new and desire to secure by Letters Patent, is:—

1. In a coating machine, a pair of transverse rollers, an endless feeding apron fitted around said rollers and having transverse strips upon them, elastic bands fitting 110 around said apron at predetermined distances, means for imparting longitudinal movement to the apron and bands, a pair of transverse rollers, an endless open work apron upon said rollers, means for rotating 115 said rollers, transverse rotary supports above the ends of said apron, elastic endless bands fitting around such supports and slightly above the open work apron and registering with the feeding bands, means for coating 120 blanks during their movement, and means for exposing the coated blanks from the open work apron to cooling air.

2. In a coating machine, a pair of transverse rollers, an endless feeding apron fitted 125 around said rollers and having transverse strips upon them, elastic bands fitting around said apron at predetermined distances, means for imparting longitudinal movement to the apron and bands, a pair 130

- of transverse rollers, an endless open work apron upon said rollers, means for rotating said rollers, transverse rotary supports above the ends of said apron, elastic endless bands fitting around such supports and slightly above the open work apron, and registering with the feeding bands, flexible carriers around said rotary supports, strips transversely supported at given distances upon said carriers and having pins projecting outward, means for coating blanks during their movement, and means for exposing the coated blanks from the open work apron to cooling air.
5. In a coating machine, a pair of transverse rollers, an endless feeding apron fitted around said rollers and having transverse strips upon them, elastic bands fitting around said apron at predetermined distances, means for imparting longitudinal movement to the apron and bands, a pair of transverse rollers, an endless open work apron upon said rollers, means for rotating said rollers, transverse rotary supports above the ends of said apron, elastic endless bands fitting around such supports and slightly above the open work apron, and registering with the feeding bands, means for coating blanks during their movement, vibrating means acting against the upper portion of the open work apron to vibrate the latter, and means for exposing the coated blanks from the open work apron to cooling air.
4. In a coating machine, a pair of transverse rollers, an endless feeding apron passed around said rollers, bands fitting around said apron at predetermined distances, means for imparting longitudinal movement to the apron and bands, transverse rollers, an endless open-work apron on said rollers, means for rotating the rollers, transverse rotary supports above the ends of said apron, endless bands fitting around said supports and slightly above the open-work apron and registering with said feeding bands, means for coating blanks during their movement, and means for exposing the coated blanks from the open-work apron to cooling air.
5. In a coating machine, a pair of transverse rollers, an endless feeding apron passed around said rollers, bands fitting around said apron at predetermined distances, means for imparting longitudinal movement to the apron and bands, transverse rollers, an endless open-work apron on said rollers, a rotary support above the ends of said apron, flexible carriers around said rotary support, endless bands fitting around said supports and slightly above the open-work apron and registering with said feeding bands, means for coating blanks during their movement, means for applying coating liquid from above and below said apron upon the blanks carried thereby, spraying means and means for exposing the coated blanks to cooling air.
6. In a coating machine, a pair of transverse rollers, an endless feeding apron passed around said rollers, bands fitting around said apron at predetermined distances, means for imparting longitudinal movement to the apron and bands, transverse rollers, an endless open-work apron on said rollers, a rotary support above the ends of said apron, flexible carriers around said rotary support, endless bands fitting around said supports and slightly above the open-work apron and registering with said feeding bands, means for coating blanks during their movement, means for exposing the coated blanks from the open-work apron to cooling air, and transverse means supported at given distances upon said carriers and having outwardly projecting pins.
7. In a coating machine, a pair of transverse rollers, an endless feeding apron passed around said rollers, bands fitting around said apron at predetermined distances, means for imparting longitudinal movement to the apron and bands, transverse rollers, an endless open-work apron on said rollers, means for rotating the rollers, transverse rotary supports above the ends of said apron, endless bands fitting around said supports and slightly above the open-work apron and registering with said feeding bands, means for coating blanks during their movement, a casing having open ends and means at one end of said casing for admitting a current of air against the coated articles in an oblique downward direction and against the direction of movement of such articles.
8. In a coating machine, a pair of transverse rollers, an endless feeding apron passed around said rollers, bands fitting around said apron at predetermined distances, means for imparting longitudinal movement to the apron and bands, transverse rollers, an endless open-work apron on said rollers, means for rotating the rollers, transverse rotary supports above the ends of said apron, endless bands fitting around said supports and slightly above the open-work apron and registering with said feeding bands, means for coating blanks during their movement, means for applying coating liquid from above and below said apron upon the blanks carried thereby, spraying means and means for exposing the coated blanks to cooling air.
